(57) **CLAIM**

The ornamental design for a utility tool, as shown and described in the drawings.

DESCRIPTION

FIG. 1 is perspective view of a utility tool, showing my design;

FIG. 2 is a back view of the utility tool thereof;

FIG. 3 is a front view of the utility tool thereof;

FIG. 4 is a right side of the utility tool thereof;

FIG. 5 is a left side of the utility tool thereof;

FIG. 6 is a top view of the utility tool thereof; and,

FIG. 7 is a bottom view of the utility tool thereof.

The broken (dash) lines illustrate environmental features that form no part of the claimed design.
